(57) **CLAIM**

The ornamental design for a toy wheeled vehicle, as shown and described.

DESCRIPTION

FIG. 1 is a top plan view of a toy wheeled vehicle in accordance with our new design;

FIG. 2 is a bottom plan view thereof;

FIG. 3 is an elevation view of the left side thereof, an elevation view of the right side being a mirror image thereof;

FIG. 4 is a front elevation view thereof; and,

FIG. 5 is a rear elevation view thereof.

The broken lines illustrate portions of the toy wheeled vehicle that form no part of the claimed design.

1 Claim, 2 Drawing Sheets
